UNITED STATES PATENT OFFICE.

GEORGE WILKINSON, OF PROVIDENCE, RHODE ISLAND.

DESIGN FOR A HANDLE FOR SPOONS, &c.

SPECIFICATION forming part of Design No. 22,748, dated August 29, 1893.

Application filed July 5, 1893. Serial No. 479,659. Term of patent 7 years.

To all whom it may concern:

Be it known that I, GEORGE WILKINSON, of Providence, in the county of Providence and State of Rhode Island, have invented and produced a new and original Design for Handles of Spoons and Similar Articles, of which the following is a specification, reference being had to the accompanying drawing, forming part thereof.

10 The drawing represents an obverse view of a handle, attached to the bowl of a spoon, illustrating my new design.

15 The leading features of my new design consist in the spreading base of the handle, forming its juncture with the bowl of a spoon or similar articles, the elongated-neck slightly contracted at its mid-length, the irregularly-scrolled outline above the neck gradually increasing the width of the handle toward the 20 upper end, and the contracted upper end, together with the surface ornamentation consisting of scrolled-beadings on the neck, and scrolls interspersed with shell-like conformations on the main portion of the handle, and 25 plain panels inclosed by the scrolled ornaments.

Number 2 in the drawing indicates the bowl of a spoon. The base 3 of the handle partially embraces the upper portion of the article to 30 which the handle is secured. The outlines of the base contact in curves to 4—4 to join the neck 5 the outlines of which are slightly

concave. From the upper end of the neck the outline of the handle extends outward and inward in irregular curves gradually increasing the width of the handle to 6—6, thence in contracting scrolls to the top 7 of the handle. The surface of the base 3 is ornamented by beaded edges which are continued by surface scrolls meeting at the center of the base. The 40 edges of the neck are ornamented by the beads 8—8 the lower ends of which curve inward, the central portion of the neck having the beadings 9—9 and 10—10 and the slightly-foliated ornament 11. Immediately 45 above the neck is the small panel 12 inclosed by the scrolls 13—13, and above this panel the scrolls 14—14' and 15—15 extend in outer and inner irregular lines on both sides of the panel 16 and join the scrolled ornament 17 at 50 the top of the handle, the inner surfaces of the scrolls 14' being given a shell-like appearance and the surface between the lines of scrolls being roughened.

What I claim is—

55 The design for handles of spoons and similar articles as herein shown and described.

In witness whereof I have hereunto set my hand.

GEORGE WILKINSON.
